ELECTRIC FURNACE MUFFLE
CONSTRUCTION

Thomas H. Forde, San Francisco, Calif., assignor
to Diascope Corporation Ltd., San Francisco,
Calif., a corporation of California

Application October 30, 1931, Serial No. 572,110

1 Claim. (Cl. 219—36)

The invention relates to improvements in electric furnace muffles and more particularly to the construction and arrangement of the muffle walls.

An object of the invention is to provide a muffle wall construction in which will be avoided the necessity of replacing the heat insulation material thereof, due to excessive muffle temperatures and the resultant burning or damage of the material.

Another object of the invention is to provide a muffle wall construction with the above feature, which may be made at practically no more expense than such type of walls as heretofore constructed, and will in addition afford greater economy in efficiency of operation as well as in maintenance cost.

A further object of my invention is to provide a muffle wall construction which will act to positively space the insulation material from the heating coil winding and the muffle chamber walls, and thus prevent disintegration of the same caused by flexing or amalgamation of the insulating material with said walls and windings.

A still further object of my invention is to provide a muffle wall construction surrounding the heating unit and so arranged as to reflect heat radiations emanating from said unit back into the central portion of the muffle.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claim.

Referring to said drawing:

Figure 1 is a vertical sectional view of a muffle having the walls thereof constructed in accordance with my invention.

Figure 2 is an enlarged horizontal section of the muffle taken on the line 2—2 of Figure 1.

Figure 3 is an enlarged fragmentary vertical section of the muffle taken at right angles to Figure 1.

As illustrated in the drawing, the muffle 4 is in the present form of the invention arranged to removably and operatively fit upon a base 6 of an electric furnace unit particularly designed for use in the dental profession and in dental laboratories. The muffle is formed as most clearly shown in Figure 2 with an inner wall 7 preferably of a high heat resistance refractory material, and an outer wall 8 spaced from the wall 7

and preferably made of an asbestos cement composition. The inner wall 7 which defines the heating chamber of the muffle extends completely around the top, bottom, and opposite sides of the muffle and has formed on the outer side thereof a series of circumferentially extending grooves 9 in which is disposed the electrical element 12 for heating the chamber. Electrical connection with said element is afforded from the rear portion of the muffle through a pair of conductors 13. At the front of the muffle is provided the opening 14 which affords access to the chamber and is arranged to be closed by a suitable door 16.

Heretofore, in the design of muffles, the entire space between the inner and outer walls was filled with a heat insulating material usually of a fibrous nature, and as a result, after the muffle was in service a comparatively short time, and particularly when excessive temperatures prevailed in the heating element, the insulation material, first the portions at the inner wall and then the portions more remote, slowly chemically united with the windings of the heating elements and the refractory material on which the element was wound to subsequently render the element and support therefor useless, whereby a dismantling of the entire muffle and a replacement of the inner wall and the winding thereon became necessary. With the muffle wall construction of my invention, such damage to the heating unit, that is the inner walls and windings, and the necessity of replacement are entirely avoided.

As will be clear from Figure 2, there is interposed between the inner and outer walls an intermediate wall 17 which is preferably disposed in close proximity to but in spaced relation from such wall so as to define therebetween a comparatively narrow air space or chamber 18. The wall 17 is preferably formed of glazed refractory material and is in the nature of a shield for the insulating material 19 which fills the comparatively large space 21 between such wall and the outer wall 8. As the chamber 18 and wall 17 are as here shown comparatively narrow, practically the full space between the inner and outer walls is still available for the insulating material and in addition the trapped air in chamber 18 of itself provides a heat insulating medium of extremely low conductivity. It will now be clear that the interposition of the wall 17 between the insulating material and the heating coil windings effectively prevents these materials from contacting and therefore eliminates the harmful chemical union hereinbefore referred to. There is, however, an additional function of the wall 17

which comprises the reflection of heat radiations emanating from the heating element when the latter and the refractory on which it is wound are heated to such a degree that the frequency of certain of the heat radiations therefrom extend well into the visible spectrum. It will of course be clear that as the heating unit warms, the heat therefrom may escape outward only by the three methods of heat transfer to wit, convection, conduction and radiation. Since the air surrounding the heating unit is trapped, and the air space itself too narrow to permit appreciable circulation, the transfer of heat by convection from the heating unit to the wall 17 is extremely slight. It will further be noted that the outward transfer of heat through the air space by conduction is also small due to the very low thermal conductivity of air. Heat radiations, however, emanating from the heating unit undulate through the ether and are therefore freely transmitted through the air space surrounding the heating unit. At low temperatures the frequency of the heat radiations are comparatively low, and since radiation is a function of both the temperature and the frequency, the heat lost in this manner is comparatively small. As the temperature of the unit is increased the latter will begin to glow until at a maximum temperature, the heating unit emanates a considerable amount of light. Under this latter condition there is an extremely large heat radiation from the unit. Heretofore in the construction of muffles the insulation surrounding the heating unit readily absorbed the heat radiation from the heating unit and thus this heat was entirely lost. In my muffle, however, the wall 17 is arranged to reflect this radiated heat back to the heating unit. In

order that the wall may so function it is preferably made of a white plastic compound with a smooth glazed inner surface. Inasmuch as the air space acts to prevent the transfer of heat by either convection or conduction to the inner side of this wall the same will remain comparatively cool and maintain its smooth, light colored reflecting surface. On the other hand since the air space freely transmits radiated heat there is practically none of this heat absorbed in the air space and thus practically all of the radiated heat reflected from the inner surface of the wall 17 is confined and convertible into useful energy.

Preferably the intermediate wall or shield 17, as well as the inner wall, extends into and removably fits in a groove 21 in the front wall portion of the muffle chamber so that the shield may be readily removed with the inner wall when the heating coils are to be replaced.

It will now be seen that the muffle wall construction of my invention is well adapted to the accomplishment of the objects hereinbefore referred to.

I claim:

In a muffle of the character described, a heated muffle casing, an outer casing surrounding said muffle casing, fibrous heat insulation material mounted between said outer casing and muffle casing, and an intermediate casing of plastic composition immediately surrounding said muffle casing and spacing therefrom said insulation material, the inner side of said intermediate casing facing said muffle casing being spaced therefrom and glazed to reflect back to said muffle casing radiant heat from said muffle casing.

THOMAS H. FORDE.
